UNITED STATES PATENT OFFICE.

EMIL F. TUBACH, OF BERNICE, PENNSYLVANIA.

MINE-CAR DOOR.

1,221,112.

Specification of Letters Patent.

Patented Apr. 3, 1917.

Application filed September 5, 1916. Serial No. 118,544.

To all whom it may concern:

Be it known that I, EMIL F. TUBACH, a citizen of the United States, residing at Bernice, in the county of Sullivan and State of Pennsylvania, have invented certain new and useful Improvements in Mine-Car Doors; and I do declare the following to be a full, clear, and exact description of the invention, such as will enable others skilled in the art to which it appertains to make and use the same.

This invention relates to improvements in mine cars, particularly the door structures thereof.

23 The principal object of the present invention is to provide an improved mine car door of simple construction which will automatically open after the car has reached the tipple, a catch previously having been released.

26 The advantage of this resides in the fact that the retaining catch may be opened before the car reaches the tipple and still prevent the coal from forcing its way out, the inclination of the car on the tipple causing the opening of the door.

An additional object is to provide an improved mine car door which can be inexpensively manufactured and one which will be very efficient in operation.

29 With these and other objects in view, my invention resides in the novel features of construction, combination and arrangement of parts which will be hereinafter more particularly described and claimed.

35 In the accompanying drawings:

Figure 1 represents an end view of a mine car showing my improved door construction in elevation;

Fig. 2 is a side elevation of one end of the 40 car showing parts broken away to more clearly illustrate the structure of the door, the retaining latch being in operative position, thereby holding the door closed;

Fig. 3 is a similar view showing the car 45 on the tipple and the door just beginning to open;

Fig. 4 is still another view similar to Fig. 2 showing the door partially opened;

Fig. 5 shows the door opened to its fullest 50 extent;

Fig. 6 is a horizontal section on the line 6-6 of Fig. 1;

Fig. 7 is a detail perspective view showing the manner in which one end of the door is 55 journaled to the car; and

Fig. 8 is a similar view of one part of the door locking means.

It is well known that mine cars after leaving the shaft of the mine are run on tracks to a suitable point of discharge where they 60 are emptied usually by means of an ordinary tipple. In emptying the cars in this manner, one end is provided with a movable door which is opened when the car has run on the tipple and been inclined. Ordinarily 65 this door cannot be unlocked until the car is inclined because of the fact that the weight of the coal will force the same open. With my invention, the door can be released or unlatched while the car is still on the horizontal portion of the track, and before it reaches the tipple, said door remaining 70 closed until it is inclined and the coal forces the same open.

In carrying out this object I have provided an ordinary mine car designated in the drawings by the numeral 1, with an improved door structure which will be more particularly described later. The car has the usual sides 2, bottom or floor 3, and running gear 4, the wheels of the latter running on ordinary tracks 5. A portion of the tipple 6 is shown in Figs. 3, 4, and 5, and may be of any preferred or suitable design.

The door 7 is formed of two parts 8 and 9, the longitudinal edges of which are spaced apart as shown at 10. These two parts of the door are held together by retaining bars 11 formed of strap metal and secured thereto by suitable fastening elements 12. One 85 of these retaining straps or bars 11 is disposed at each edge of the door and on each side thereof, and extends from the top to the bottom edges. Between the parts 8 and 9 of the door is disposed a rotatable shaft 13, 90 the ends of this shaft being retained in operative position by means of the straps 11 which are disposed on each side thereof, said shaft having cranks 14 connected with its ends.

The shaft 13 and the cranks 14 may be formed of the same bar if desired, and the upright portions 15 of the cranks are disposed at the ends of the portion 8 of the door, the ends of the latter being cut away 105 as shown at 16 to receive the same. The horizontal parts 17 of the cranks are journaled to the sides 2 of the car, angle metal brackets 18 being secured to the upper edge of the sides for this purpose. The hori- 110

zontal flanges of these angle brackets are recessed adjacent one end as shown at 19 to allow the cotter pin 20 or other retaining means carried by the cranks to clear said flanges.

From this description it will be seen that since the door 7 is rotatably mounted on the shaft 13 and the cranks of the latter are journaled in the angle brackets 18, said door 10 may readily swing outward around said shaft or may be raised upward when the cranks are elevated by any means. It will also be noted when the door is pressed outwardly by any means, such as coal within, 15 it will be raised because of its peculiar mounting.

In order to retain the cranks in a substantially vertical position and thereby retain the door in the position shown in Figs. 20 1 and 2, a pair of hooked fingers 21 is provided, one being disposed on each end of a rock shaft 22. The rock shaft is journaled in suitable bearings adjacent the top of the door 7 and the fingers are disposed beyond 25 the ends of the portion 8 so that when the shaft is rocked in one direction the fingers will be disposed in engagement with the horizontal portions 17 of the cranks. They are normally retained in this position by 30 the weight of a depending handle 23 which is formed on the rock shaft. The handle 23 is retained against accidental movement by means of a pivoted latch 24 in the form of a lever. One end of said lever which forms 35 the handle is held in operative position by means of a hook or the like 24'. The rock shaft 22 is also provided with a pair of collars 24'' which are fixed thereto and disposed one adjacent each of its outermost 40 bearings which, in the present instance, are formed by the straps 11. These collars prevent longitudinal shifting of the rock shaft and hold the hooked fingers 21 in proper relation to the cranks with which they co- 45 operate.

From the several figures it will be seen that the structure which has just been described is all disposed adjacent the top of the door 7. In order to hold the bottom 50 portion of the door against outward movement additional catches in the form of fingers 25 depend therefrom and coöperate with seats on the bumper 26 of the car. The fingers 25 are preferably formed by extending 55 the outer straps 11 below the bottom edge of the door as clearly shown in Figs. 2, 4, and 5. These seats are formed by right angular members 27 constructed of angle metal and are secured by their horizontal 60 flanges 28 to said bumper 26 or the adjacent parts of the car. One arm of each right angular member 27 is disposed inwardly while the other is disposed longitudinally of the car as shown in Fig. 6. It is between 65 the upright flanges of the first mentioned

arms and the edge of the floor 3 that the fingers 25 are disposed.

The operation of the door structure hereinbefore described, assuming that the car upon which it is mounted has been loaded 70 with coal, is as follows: The loaded car is run on its tracks 5 until it reaches a point adjacent the tipple 6, whereupon the latch 24 is disengaged from the handle 23, thus permitting the rock shaft to rotate in order 75 to release the hooked fingers 21 from the cranks 14, which are held against movement so long as the handle 24 is down in the position shown in Figs. 1 and 2. The door does not begin to open, however, after the latch 80 24 has been released until the car has reached the tipple and been inclined as shown in Figs. 3, 4, and 5. This inclination causes the coal in the car to move by gravity against the door 7, and since the lower 85 edge of the door is held by the fingers 25, the upper part will be forced outwardly as shown in Fig. 3, the cranks 14 readily permitting this outward movement. The continuous pressure of the coal on the upper 90 part of the door gradually forces the same outwardly until the fingers 25 are forced clear of their seats, whereupon the coal forces its way between the lower edge of the door and the bottom of the car. The door 95 is now carried by this movement of the coal upwardly and outwardly around the shaft 13 and by the cranks 14 into the positions illustrated in Figs. 4 and 5, Fig. 5 showing the door opened to its fullest extent. The 100 outrushing coal retains the door thus until the car is completely emptied, whereupon it is moved by gravity into more of a vertical position.

After the car has been emptied and moved 105 off of the tipple onto its horizontal tracks the door may be readily closed and locked by first inserting the fingers 25 in their seats, the upper portion of the door 7 during this movement being inclined outwardly. The 110 upper part of the door is then moved inwardly until it is substantially vertical or until the outer ends of the rock shaft engage the horizontal portions 15 of the cranks. The rock shaft is next rotated so as to dispose 115 the hooked fingers 21 in engagement with the horizontal parts of the cranks, the handle 23 being then disposed downwardly so that it may be engaged by the latch 24.

From the foregoing description taken in 120 connection with the accompanying drawings, it is obvious that I have invented a much improved mine car door which may be operated very efficiently. The simplicity of the construction will allow the same to be 125 manufactured rather inexpensively. It is unnecessary to build a specially constructed car in order to use a door constructed in accordance with my invention, as ordinary cars already built may be readily equipped. 130

I claim:

1. The combination with a door opening, of a door therein, a crank extending from each side of said door and journaled in the 5 side of said door opening, and a catch, said catch being released by pressure against the inside of said door.

2. The combination with a door opening, of a normally closed door therein, cranks extending from opposite edges of said door, 10 said cranks being journaled in said door and in the sides of said door opening, means for holding said cranks to prevent the opening of said door, and a catch, said catch being released, when said means is disengaged 15 from the cranks, by pressure from the inside of said door.

3. The combination with a door opening, of a normally closed door therein, cranks extending from opposite edges of said door, 20 said cranks being journaled in said door and in the sides of said door opening, a hooked finger pivoted on said door to engage one of said cranks to hold the same against movement, and a catch on said door.

4. The combination with a door opening, of a normally closed door therein, cranks extending from opposite edges of said door, 30 said cranks being journaled in said door and in the sides of said door opening, a rock shaft on the door, its ends extending beyond the same, catches on the ends of said shaft to engage said cranks to hold the same against movement, means to prevent rotation of said rock shaft, and a catch to aid 35 in holding said door normally closed.

5. The combination with a door opening, having a two-part door therein, the adjacent edges of the parts of said door being spaced apart, a rotatable shaft disposed between 40 said adjacent edges, means for retaining the two parts of said door together, said means also holding said shaft in operative position, cranks on the ends of said shaft, the free 45 ends of said cranks being journaled in the sides of said door opening, and means for holding said cranks against movement.

6. The combination with a door opening, of a two-part door therein, the adjacent edges of the parts of said door being spaced apart, a rotatable shaft disposed between 50 said adjacent edges, retaining straps disposed at each end of said door and on each side thereof, to hold the two parts of the same together, said straps also retaining said shaft in operative position, cranks on the opposite ends of said shaft, the free ends of 55 said cranks being journaled in the sides of said door opening, and means for holding said cranks against movement.

7. The combination with a door opening, of a normally closed door therein, a supporting bracket therefor comprising a shaft 60 extending across said door and rotatably mounted thereon, a crank arm on the ends of

said shaft, the free ends of said crank arms being journaled in the sides of said door opening, a rock shaft on said door, its ends extending beyond the same, catches on the end of said rock shaft to engage the crank 70 arms to hold the same against movement, and means to prevent rotation of said rock shaft.

8. The combination with a door opening, of a normally closed door therein, a supporting bracket therefor comprising a shaft 75 extending across said door and rotatably mounted thereon, a crank arm on the ends of said shaft, the free ends of said crank arms being journaled in the sides of said door opening, a rock shaft on said door, its ends extending beyond the same, catches on the ends of said rock shaft to engage the crank arms to hold the same against movement, a handle depending from said rock 80 shaft, and a pivoted catch to engage said handle to prevent rotation of said rock shaft.

9. The combination with a door opening, of a two-part door, the adjacent edges of 90 the parts of said door being spaced apart, a rotatable shaft disposed between said adjacent edges, means for retaining the two parts of said door together, said means also holding said shaft in operative position, 95 cranks on the opposite ends of said shaft, the free ends of said cranks being journaled in the sides of said door opening, a rock shaft carried by one part of said door, hooked fingers on the opposite ends of said 100 rock shaft to engage said cranks to hold the same against movement, and means to prevent rotation of said rock shaft.

10. The combination with a door opening, of a normally closed door therein, 105 cranks extending from opposite edges of said door, said cranks being journaled in the sides of said door opening, a finger depending from the bottom of said door, and a seat carried by the bottom of said door 110 opening, said finger being disposed in said seat, and means to prevent movement of said cranks.

11. The combination with a door opening, of a two-part door, the adjacent edges 115 of the parts of said door being spaced apart, a rotatable shaft disposed between said adjacent edges, retaining straps disposed at each end of said door and on each side thereof to hold the two parts of the same 120 together, said straps also retaining said shaft in operative position, the straps on one side of said door being extended beyond the bottom edge thereof to provide fingers, seats in the bottom of said door opening to receive said fingers, cranks on the opposite ends of said shaft, said cranks being journaled in the sides of said door opening, and means to prevent movement 125 of said cranks.

- 4
12. The combination with a door opening, of a two-part door, the adjacent edges of the parts of said door being spaced apart, a rotatable shaft disposed between said adjacent edges, retaining straps disposed at each end of said door and on each side thereof to hold the two parts of the same together, said straps also retaining said shaft in operative position, the straps
  10. on one side of said door being extended beyond the bottom edge thereof to provide fingers, seats in the bottom of said door opening to receive said fingers, cranks on

the opposite ends of said shaft, said cranks being journaled in the sides of said door 15 opening, a rock shaft carried by said door, and hooked fingers on the ends of said rock shaft, said fingers engaging said cranks to prevent movement thereof.

In testimony whereof I have hereunto set 20 my hand in the presence of two subscribing witnesses.
